[57] CLAIM

The ornamental design for a foot warmer cushion, as shown and described.

DESCRIPTION

FIG. 1 is a top, front, and left side perspective view of a foot warmer cushion showing my new design;
FIG. 2 is a front elevational view thereof, showing the mouth of the cushion in an open condition;
FIG. 3 is a left side elevational view thereof, the right side being a mirror image of that shown;
FIG. 4 is a rear elevational view thereof; and,
FIG. 5 is a top plan view thereof, the bottom being a mirror image of that shown.

FIG 1

FIG 2

FIG 3
